METHOD AND APPARATUS FOR REMOVING
AMPLITUDE MODULATION

Edward H. Lange, Baltimore, Md.

Application October 25, 1941, Serial No. 416,434

11 Claims. (Cl. 178—44)

This invention pertains to a method for removing amplitude modulation from an alternating voltage, for example an alternating carrier-frequency voltage having amplitude-modulation, and with particular reference to a frequency-modulated carrier voltage having undesired amplitude-modulation, and to several simple circuit means carrying out the method.

The principal object of this invention is to provide a method and several forms of apparatus applying the method, for removing amplitude-modulation of an alternating voltage. Another object is to provide a simple method and means for removing a high percentage of amplitude-modulation, that is for removing amplitude-modulation from an alternating carrier-voltage having a high percentage of amplitude-modulation. Still another object is to provide a simple method and apparatus for annulling amplitude-modulation present in a high percentage, without substantial reaction upon and modification of carrier wave-form.

These objects, and others, and important features of this invention are hereinafter further pointed out in the specification and appended claims, and will be better understood by reference to the drawings.

Referring to the drawings,

Fig. 1a illustrates a conventional stage of thermionic amplifier suitable for linkage with the devices of this invention, for applying amplitude-modulated voltage.

Fig. 1 illustrates a circuit with a single thermionic tube for carrying out the method of this invention.

Fig. 2 shows an amplitude-modulation removing circuit employing two thermionic tubes, and is a modification of Fig. 1.

Fig. 3 illustrates an alternative form of link for interconnecting a stage such as is shown in Fig. 1a with the circuits of Fig. 1 or Fig. 2.

Fig. 4 illustrates an alternating carrier-voltage having amplitude-modulation.

Fig. 5 illustrates a typical characteristic of grid transconductance in relation to negative grid bias employed in the circuit of Fig. 1 and Fig. 2.

Fig. 6 illustrates an amplitude-modulation removing circuit employing the method of this invention in a further modification of apparatus.

Fig. 7 illustrates another relationship between cathode-plate conductance and negative grid bias, employed with the modification of Fig. 6 for carrying out the method of this invention.

In Fig. 1a, at 4 is a thermionic pentode, hav-

ing a cathode 4e, control-grid 4d, screen-grid 4c, and plate 4a, the suppressor 4b being connected to the cathode. Plate 4a is connected to an output terminal 2, and is supplied with continuous voltage through a resistance 4i, by the conductor 4k, which leads to a source of continuous voltage such as 44, Fig. 1, and screen-grid 4c is connected to 4k through a resistance 4h. A condenser 4l serves to by-pass alternating current of the screen-grid to the output terminal 2a, and similarly the condenser 4p serves to by-pass alternating current of the high-potential side of the conductor 4k to the terminal 2a. The terminal 2a is grounded at 4y. At 4g is a heater element for the cathode 4e, one terminal being connected to 2a, and the other terminal 4j being connected to a source of power such as 44, Fig. 1. The input terminal 4a is negatively biased with reference to the cathode 4e, by the resistance 4f, the condenser 4g serving to by-pass alternating currents. It is understood that an alternating voltage having amplitude-modulation is impressed across 1—1a, and similarly that the output terminals 2, 2a, supply an alternating voltage having amplitude-modulation, for the purpose of this invention.

In Fig. 3, an alternative form of output link circuit is shown. The inductance 45 either replaces or is connected in series with a resistance 30 such as 4i, by means of the terminals 2' and 2'a. Coupled with the inductance 45, by mutual inductance, is the inductance 46, tuned by condenser 48, and leading to the terminals 2b and 2e. Similarly coupled with 45 is the inductance 47, tuned by condenser 49, leading to the terminals 2c and 2d.

Referring to Fig. 1, at 5 is a thermionic tube including a triode with plate 10, grid 13, and cathode 9, and a pentode with plate 7, suppressor 8, screen-grid 12, grid 11, and cathode 16. In close proximity with cathode 16, is a diode-plate 6. The cathode 16 and cathode 9 are connected to the terminals 14, 15, the terminal 16 being connected through the switch 35 to the power source 44, when 35 is closed, and through the resistance 37 and conductor 36 back to 14. The suppressor 8, is connected to 15. At 29 and 30, are high resistances, 29 being connected across the input terminals 2 and 2a by means of condenser 27 and condenser 28; resistance 30 being similarly connected by means of condensers 32 and 41, it being understood that the condensers are of low impedance in relation to 29 and 30, the condensers 28 and 32 serving as stopping condensers for continuous voltage upon terminal

2, and the condensers 27 and 41 serving as by-pass condensers for carrying alternating currents of 28 and 38 respectively, directly to the terminal 2a. One end of resistance 38 terminates at 2b, the other end at 2e; similarly one end of 28 terminates at 2c, the other end at 2d. For application of amplitude-modulation to the circuit of Fig. 1, for the purpose of removing said modulation, the terminal 2 is connected to the terminal 2 of Fig. 1a, and likewise the terminal 2a is connected to the terminal 2a of Fig. 1a. Alternating voltage with amplitude-modulation, is thus provided between the terminals 2b and 2e, and between the terminals 2c and 2d.

The terminal 2b is connected to the grid 13, of the triode 9-10-13. The plate 10 is connected through the resistance 24 and conductor 38 to a source of continuous voltage 39, the negative terminal of 39 being connected to the common conductor joining terminal 2a with 3a. The resistance 24 is of the order of magnitude of the cathode-plate resistance, 9-10, or larger, for the purpose of supplying an amplified amplitude-modulated alternating voltage in relation to the alternating voltage impressed upon 13. At 17 is a high resistance connected from 15 to the diode-plate 6, the resistance 17 being of such value in relation to the thermionic resistance 6-16, that substantially direct proportionality exists between amplitudes of applied alternating voltage and rectified voltage across 17, in a manner well understood. At 24a is a variable connector for applying a selected amount of amplified amplitude-modulated alternating voltage to the diode-plate 6, through the stopping condenser 25. The condenser 25 has a low impedance relative to 24; the condenser 21 across 17 is provided to cooperate with 17 to reduce the magnitude of fluctuations of rectified voltage, in relation to frequencies of the order of magnitude of the carrier frequency. Unidirectional voltage is provided across 17, which varies directly with the amplitudes of the amplitude-modulated alternating voltage across the terminals 2b-2e, and which is larger than the respective amplitudes because of amplification of the triode 9-10-13.

Connecting the diode-plate 6 with the terminal 2d of the resistance 28, is a choke coil 18, one end of the choke coil being connected to the common connection 2a-3a through the condenser 19. The choke 18 and condenser 19 are provided to substantially eliminate variations in the unidirectional voltage across 17 of carrier frequencies, but to permit variations in the unidirectional voltage corresponding to frequencies of amplitude-modulation. This unidirectional voltage varying with frequency of amplitude-modulation is impressed upon the grid 11 of the pentode through the resistance 29, and the potentiometer 33a, which is supplied from the source of continuous voltage 39, when the switch 40 is closed. Both unidirectional voltage across 17 and potentiometer provide negative biasing of the grid 11. The grid 13 of the triode, is returned through the resistance 38 and fixed negative bias 34, to the common connection 2a-3a.

The plate 7 of the pentode is connected through a resistance 31, and conductor 45a to the source of continuous voltage 39, and the by-pass condenser 42 serves to carry alternating current of the resistance 31 directly to the common connection 2a-3a, which is grounded at 44. The resistance 31 is proportioned to be very small in relation to the alternating current cathode-plate resistance, 16-7 of the pentode, so that substan-

tially all of the alternating current resistance of the circuit 16-7-31-42-16 is comprised within the thermionic pentode. Connecting 31 with the output terminal 3 is a condenser 43, and across the output terminals 3-3a is a high resistance 26. The resistance 26 is high in relation to 31, and the impedance of condenser 43 is negligible in relation to 31, so that the alternating output voltage across 3-3a is substantially the same as the alternating voltage across 31. The screen-grid 12 is connected by way of the conductor 45 to the source of continuous voltage 39, and the condenser 20 serves to by-pass alternating currents of the screen-grid directly to the common connection 2a-3a.

Referring to Fig. 5, at 53, 54a, a typical characteristic curve relating grid transconductance with negative grid bias is illustrated, for the type of pentode employed in this invention, in Fig. 1 and Fig. 2. An important feature of this invention, is the utilization of a unique relationship found to exist in numerous conventional pentodes, such for example as the pentodes at present manufactured and designated by numbers 78, 9003, 956, 6SK7, 6U7-G, and others, wherein a fixed negative bias voltage $-E_c$ determines a reciprocal relationship between grid transconductance and negative grid bias in excess of the fixed negative bias, which exists over a substantial and useful range of negative grid voltages, many times the magnitude of the carrier voltage employed. Numerous tubes provide such a useful reciprocal relation over a range of 10 to 20 volts negative, in excess of a predetermined negative bias, as illustrated for example, between indices 50 and 51. The solid line 54a indicates a true rectangular-hyperbola with reference to the axis 54 defined by the specific negative grid bias $-E_c$, and the dotted curve 53 indicates the beginning of divergence of the actual characteristic from this relationship. Thus it will be noted that the alternating current flowing through the circuit 16-7-31-42-15-16 is determined by the product of the grid transconductance g_m and the varying amplitude of the amplitude-modulated alternating voltage impressed upon the grid 11. The grid transconductance however, is made to vary in a reciprocal relation with the excess negative bias, which in turn varies directly with the amplitudes of the modulated alternating voltage, so that the product of any of the various alternating voltage amplitudes with their respective resultant grid transconductance is constant. Thus the ratio of alternating current through 31 to the alternating current conductance of 31 is constant, and there is a resultant alternating voltage of constant amplitude across 31, and across the output terminals 3-3a. In Fig. 4, a carrier voltage of amplitude e_0 with amplitude-modulation resulting in the various amplitudes $e_1, 2e_1, 4e_1, 6e_1$, is shown. In Fig. 5, these voltages are shown in relation to the respective grid transconductance, determined by the negative unidirectional voltages $Ke_0, 2Ke_0, 4Ke_0$, and $6Ke_0$, resulting from the amplification of K times the various amplitudes and subsequent rectification.

An alternative means of applying the amplitude-modulated alternating voltage to the terminals 2b-2e, and to the terminals 2c-2d, is illustrated in Fig. 3. In this instance, the resistances 28 and 30, condensers 32, 28, 27, 41, are not employed, the terminals 2b-2e of Fig. 3 being directly connected to 2b-2e of Fig. 1, and the

terminals 2c—2d of Fig. 3 being similarly connected to 2c—2d of Fig. 1.

Referring to Fig. 2, a modification of Fig. 1 is shown, employing a pentode 5a and a separate triode 5b. The input terminals for application of an amplitude-modulated alternating voltage are shown at 2'b—2'e, and at 2'c—2'd, it being understood that either a linkage-connection as shown in Fig. 1 at 29, 30, 21, 28, 32, 41, using a resistance-condenser combination, or the arrangement of Fig. 3, can be employed. In using the linkage of Fig. 3, the terminal 2b is connected to 2'b, 2e to 2'e, 2c to 2'c, and 2d to 2'd.

Across the terminals 39a and 39b is a source of continuous voltage, and a resistance 39d, the continuous voltage being for the purpose of supplying the plate 10b, plate 7a, and screen-grid 12a, the negative terminal 39a being grounded. Across 36a—36b is a source of continuous voltage for supplying the heater elements 9 and 16, of triode 5b and pentode 5a respectively. One terminal of each heater element is connected to the common conductor 2a—3a, the other is connected by 36 to the positive terminal 36b. Negative bias for the triode 5b is provided by means of the resistance 34b connected between the cathode 8a and common conductor 2a—3a. The condenser 34a is provided to by-pass alternating currents of carrier frequencies. The triode 5b performs the same function of amplifying the impressed amplitude-modulated alternating voltage as in Fig. 1, and likewise the pentode 5a performs in the same manner as the pentode of Fig. 1. A resistance 25a connects the diode-plate 6a with resistance 17, the opposite end of resistance 17 being connected to the cathode 16a. Amplified modulated alternating voltage is impressed upon the diode-plate 6a through the stopping condenser 25. Provision is made at the terminals 33c and 33d for the introduction of a fixed negative bias such as 33a, however the terminals 33c and 33d are connected together when a thermionic tube is employed at 5a capable of providing the requisite reciprocal relationship of grid transconductance with negative grid bias without fixed negative bias, and relative to zero grid bias.

Referring to Fig. 6, a further modification of apparatus is shown for carrying out the method of this invention, the larger conductance of the circuit, corresponding to 31, Fig. 1 or Fig. 2, is in this instance the cathode-plate thermionic conductance of a triode, modified by rectified amplified amplitude-modulated alternating voltage to also maintain a constant ratio between alternating current and magnitude of alternating current conductance of the larger conductance. At 5c is shown a pentode having cathode 16c, grid 11c, suppressor 8c and plate 7c. The suppressor 8c is connected to the cathode 16c. At 39b—39c is a source of continuous potential, across which is the resistance 39d. The screen-grid 12c is connected by conductor 45 to the resistance 39d. The plate 7c is energized through a resistance 31c connected by conductor 46 to the positive terminal 39b. Input terminals for applying amplitude-modulated alternating voltage are shown at 2'' and 2''a connected to the input resistance 29c through condensers 28c and 28d, the grid 11c being negatively biased by voltage drop through the resistance 60, caused by flow of plate-cathode current 7c—16c, the condenser 59 serving to by-pass alternating currents and having negligible impedance relative to any of the resistance elements. At 74 is a

variable connector connected to resistance 31c for applying a selected amount of amplified amplitude-modulated alternating voltage through the stopping condenser 25c to the diode-plate 6c, and to the resistance 17c which is connected to the cathode 16c. At 70 is a double-triode tube, one of the triodes having the plate 66, grid 69, and cathode 71, the other triode having plate 67, grid 68, and cathode 72. The heater elements 76 and 77 of the cathodes 72 and 71 are connected together as shown, one terminal being connected to the output terminal 3a, which is grounded at 4y, the other terminal being connected by the conductor 36 to a source of power such as indicated at 36b, Fig. 2. The cathode 71 is connected to 3a as shown. The plate 66 is supplied by a continuous voltage, for example by connection to resistance 39d through conductor 58a and resistance 58. Connected from the plate 66 to the terminal 3a is a resistance 59. The triode 66—69—71 has a substantially straight-line relation between continuous current conductance of the cathode-plate 71—66 and negative grid bias voltage applied to grid 69, from the rectified amplified modulated alternating voltage produced across 17c. The terminal 39c is negative relative to the grounded portion 4y of the resistance 39d. One end of the bias resistance 60 is connected to adjustable connector 74 and to resistance 75, which resistance is shunted across the terminal 39c and ground connection 4y. Thus, relative to the cathode 71 there are two opposite continuous voltages upon the grid 69, when there is no alternating carrier voltage across the terminals 2''—2''a. The normal, and substantially constant operating bias of the pentode 5c which exists across 60, is opposed by a greater negative biasing voltage across 75. This is adjusted by means of 74 to give a resultant negative bias upon grid 69. When there is a rectified voltage across 17c, this unidirectional voltage is superposed upon the resultant initial negative bias of grid 69, uniformly decreasing the continuous current conductance of 66—71 in relation to magnitude of rectified voltage across 17c. The conductances 58, and 59, are proportioned in relation to the thermionic conductance 66—71 so that as the thermionic conductance 66—71 uniformly decreases, the continuous potential difference across 59 uniformly increases, in a manner well understood. Connected from the plate 66 to the terminal 3a is a by-pass condenser 59a for by-passing any variations in cathode-plate current through 66—71 occasioned by variations in the unidirectional voltage across 17c of carrier frequency. A condenser 75a across 3a and 74, of negligible impedance in relation to any of the circuit resistances, serves to by-pass alternating currents around 75. Adjustably connected to 59 by the connector 73 is the grid 68, the grid 68 being connected through the choke coil 65, and to the terminal 3a through the condenser 63. The choke 65 and condenser 63 operate to remove any residual fluctuations in the unidirectional voltage of carrier frequency. Connected from the positive conductor 46 to the terminal 3a, is high-resistance potentiometer 61—62, the cathode 72 being connected by adjustable connector 61a to 62. The by-pass condenser 64 having negligible impedance in relation to cathode-plate impedance of 67—72, connects 72 with the terminal 3a. The plate 67 is supplied with continuous voltage from the conductor 46 through the high-impedance choke coils 54, 54a, the impedance of 54 and

54a being very high in relation to the magnitudes of alternating current conductance employed between 67—72. The condenser 20, connected between screen-grid 12c and 3a serves to by-pass currents of carrier frequency. The condenser 42 connected between the terminal 3a and the conductor 46 serves to carry the alternating currents of the resistance 31c directly to the terminal 3a. The plate 67 is connected through a resistance 57, stopping condenser 56 and variable connector 55 to the resistance 31c. The resistance 57 is very high in relation to any magnitudes of alternating current resistance employed between 67—72, so that alternating currents traversing the path 16c—7c—31c—56—57—67—72—64—75a—59—16c are substantially unchanged by any modification employed in the thermionic conductance 67—72 when modulated carrier voltage is impressed upon 2''—2''a.

It will be noted that when there is no carrier voltage impressed across 2''—2''a, that relative to cathode 72 the grid 68 has a positive voltage across 59 opposed against a negative voltage across part of 62. The connector 61a is normally adjusted to provide negative bias upon grid 68 in excess of the positive bias across 59, sufficient to substantially cut off the cathode-plate current between 67—72. With carrier voltage present upon 2''—2''a, the grid 68 becomes correspondingly less negatively biased, and the alternating current conductance of 67—72 is correspondingly increased. The output terminal 3 is connected to the plate 67 through a stopping condenser 43, and connected to the terminal 3a through a resistance 26a. The resistance 26a is very high in relation to the resistance 67—72 employed between cathode-plate, and the impedance of condenser 43 is negligible in comparison with 26a; the alternating voltage across 3—3a is thus substantially the same as across 67—72, and the resistance 26a also provides a conductive connection between 3 and 3a for use in a subsequent stage. The alternating voltage across 67—72 is thus determined by the ratio between the alternating current flowing therethrough and the magnitude of the alternating current conductance of 67—72, each quantity of which, through the structure described varies directly with the amplitudes of the amplitude-modulated voltage impressed upon 2''—2''a.

Referring to Fig. 7, a typical characteristic employed in this invention for the triode 67—68—72 is illustrated, relating cathode-plate alternating current conductance with negative grid bias. At 0 is the position of zero grid bias, and at 0' is the position of cut off of cathode-plate current, occasioned by a negative bias of magnitude $-E_g$. At g, 2g, 4g, 6g, are shown relative magnitudes of cathode-plate conductance for the alternating voltage amplitudes e_g , $2e_g$, $4e_g$, and $6e_g$, of the modulated carrier voltage. The characteristic illustrated in Fig. 7, employed in this invention, is typical of numerous conventional triodes, such for example as those designated by numbers 6L5-G, 85, 6C5, and others. As employed in Fig. 6, the grid transconductance of the pentode is substantially constant for the relatively small voltage amplitude of signal used, and with the substantially constant negative bias used. The amplitudes of the alternating currents set up in the circuit

16c—7c—31c—56—57—67—

72—64—75a—59—16c,

are thus proportional to the alternating voltages

impressed upon 2''—2''a, and the conductance across 67—72 to these currents is also varied in direct proportion to said alternating voltages, providing a constant amplitude alternating voltage across 67—72, and across 3—3a.

In the circuits above described, the conditions providing a constant ratio between alternating current magnitude in the principal circuit noted in each instance, and the magnitude of the larger conductance, whether the larger conductance is a thermionic conductor 67—72 as in Fig. 6, or a conductor 31 as in Fig. 1 or 2, are attainable with resultant gain of amplitude between the input terminals and the output terminals 3—3a. An important feature of the method is the smallness in variation of conductance over a cycle of impressed frequency. In Fig. 5, and Fig. 7, the alternating voltages shown are large in relation to a range of negative bias voltages of ten to twenty volts, for example, in order to more clearly illustrate the principle; however in actual use the alternating voltages are relatively smaller than shown, and the conductance over a cycle is more nearly constant, thus providing alternating currents of carrier frequencies without substantial alteration of wave-form, and without introducing extraneous frequencies. Another feature of importance, is the capability of removing amplitude-modulation when the impressed carrier voltage has a high percentage of amplitude-modulation. In terms of the ratio of highest amplitude to lowest amplitude, designated for example by ρ , the modulation index is

$$M = \frac{\rho - 1}{\rho + 1}$$

the modulation index M being otherwise defined as the ratio of difference between extreme amplitude and the carrier amplitude, to the carrier amplitude, the latter being the arithmetic mean of the extreme amplitudes. Thus the larger the ratio ρ , the higher is the percentage modulation, 100M, e. g., if $\rho=10$, $M=9/11$, or about 82 percent amplitude modulation. The method of this invention permits of the employment of a large ratio between the highest and lowest amplitudes, as indicated in reference to the application of Fig. 5 and Fig. 7.

Having thus described several illustrative embodiments of my invention, it will be evident that changes can be made in the form and arrangement of parts without departing from the spirit of my invention, as set forth in the appended claims, and I do not therefore limit the scope of the invention to such particular embodiments, or otherwise than by the terms of the appended claims.

What is claimed is:

1. A modulation reducing device, for substantially removing amplitude modulation from an amplitude-modulated high-frequency voltage, said device having a thermionic pentode with cathode, plate, grid, screen-grid, and a suppressor connected to the cathode, capable of providing grid-transconductance variations in a reciprocal relationship with modifications of negative grid bias, power supply means for said cathode, continuous voltage means for said plate and screen-grid, an output conductance connected in series with the cathode-plate alternating current conductance, large in comparison therewith, amplifying means independent of any alternating voltages across said output conductance, and across said cathode-plate, separately amplifying said modulated high-frequency voltage, diode

means including said cathode, for rectifying said amplified modulated high-frequency voltage in direct proportion to the amplitudes of said high-frequency voltage, a norm-determining negative bias, for determining a range of negative grid voltages in excess of said bias which yields a substantially constant product of said excess bias voltage with respective magnitudes of grid-transconductance, said range being large in relation to the amplitudes of said modulated high-frequency voltage; said device having a series connection between said grid and cathode, including said norm-determining bias, said modulated high-frequency voltage, and said rectified amplified high-frequency voltage in negative bias relationship, whereby voltage of said high-frequency and substantially constant amplitude is provided across said output conductance.

2. The apparatus for removing amplitude modulation from an amplitude modulated alternating voltage, said apparatus having a thermionic pentode with cathode, plate, grid, screen-grid, and a suppressor connected to the cathode, and having diode-means including said cathode, continuous voltage means for supplying said plate and screen-grid, an output conductance connected in series with the cathode-plate alternating current conductance, and large in comparison therewith, amplifier means independently amplifying said modulated alternating voltage, independent of any alternating voltages across said cathode-plate, and across said output conductance, rectifier means including said diode-means for rectifying said amplified modulated alternating voltage in direct proportion to the amplitudes of said alternating voltage, a primary negative bias for adjusting relationship between grid-transconductance and negative grid voltages in excess of said bias, and a secondary negative bias derived from said rectified alternating voltage, connected in series with said primary bias and said modulated alternating voltage, between the cathode and the grid, whereby alternating voltage of unmodulated amplitude is produced across said output conductance.

3. The combination with a thermionic pentode having cathode, plate, grid, screen-grid, and a suppressor connected to the cathode, capable of providing grid-transconductance variations in a reciprocal relationship with modifications of negative grid bias, of circuit means for removing amplitude modulation from an amplitude-modulated alternating carrier voltage, said circuit means including input terminals for applying amplitude-modulated alternating voltage, output terminals for supplying constant-amplitude alternating voltage, continuous voltage means supplying said plate, and said screen-grid, amplifier means independently amplifying said amplitude-modulated alternating carrier voltage, independent of any alternating voltages across said cathode-plate, and across said output terminals, diode-means including said cathode, rectifying said amplified modulated carrier voltage in direct proportion to the amplitudes of said modulated carrier voltage, a norm-determining negative grid bias determining a range of negative grid voltages in excess of said bias which yields a substantially constant product of said excess bias with respective magnitudes of grid-transconductance, said range being large in comparison with amplitudes of the modulated carrier voltage, an output conductance connected to said output terminals, connected in series relation with the cathode-plate alternating current conductance,

and large in relation thereto, and a series connection between the cathode and grid, including said norm-determining bias, said rectified amplified modulated carrier voltage with negative grid-bias polarity, and said modulated carrier voltage, whereby amplified carrier voltage with unmodulated amplitude is produced across said output conductance.

4. A modulation reducing device, for substantially removing amplitude modulation from an amplitude-modulated alternating carrier voltage, said device having a thermionic pentode with cathode, plate, grid, screen-grid, and a suppressor connected to said cathode, an alternating current output conductance connected in series relation with the cathode-plate conductance of said pentode, and large in relation thereto, said alternating current output conductance comprising the cathode-plate alternating current conductance of a thermionic triode, having cathode, grid, and plate, capable of uniformly decreasing in magnitude with increase of negative bias upon said triode-grid, continuous voltage supply for the plate and screen-grid of said pentode, and the plate of said triode, amplifying means including said pentode, independently amplifying said amplitude-modulated carrier voltage, independent of any alternating voltages across said output conductance, diode rectifying means including the cathode of said pentode, rectifying said independently amplified modulated carrier voltage to a unidirectional voltage directly proportional to the amplitudes of said amplitude-modulated carrier voltage, negative bias means for biasing the grid of said triode to substantially cut off the cathode-plate current of said triode, and a polarity-conversion means impressing said unidirectional voltage upon the grid of said triode in series relation with said negative bias means,

40 to differentially positively bias said triode-grid in direct proportion to the amplitudes of said amplitude-modulated carrier voltage, whereby a substantially constant amplitude alternating carrier voltage is established across said output conductance.

5. A modulation removing circuit for removing amplitude modulation from an amplitude-modulated alternating voltage, said circuit having an alternating current input conductance connected in a series relation with an alternating current output conductance, said input conductance including thermionic amplifying means independently amplifying said amplitude-modulated alternating voltage, independent of any alternating voltages across said output conductance, said output conductance being large in relation to said input conductance, and consisting of the cathode-plate alternating current conductance of a thermionic triode, having cathode, grid, and plate, capable of uniformly decreasing with increase of negative bias of said triode-grid, a continuous voltage supply for the plate of said triode, diode rectifying means connected with said amplifying means, providing a unidirectional voltage in direct proportion to the amplitudes of said modulated alternating voltage, from said amplified modulated alternating voltage, negative bias means for setting said triode grid to substantially cut off plate current of said triode, and bias opposing means for opposing said unidirectional voltage against said negative bias, whereby said output conductance is varied in direct proportion to the amplitudes of the amplitude-modulated alternating current through said conductance, and alternating voltage of con-

stant amplitude is provided across said output conductance.

6. The apparatus for removing amplitude modulation from an amplitude-modulated alternating input voltage, said apparatus having a first thermionic tube with cathode, plate and grid, and an auxiliary plate associated with said cathode, an alternating current output conductance connected in a series relation with the cathode-plate alternating current conductance of said first thermionic tube, and large in comparison therewith, consisting of the cathode-plate alternating current conductance of a second thermionic tube, having cathode, plate and grid, continuous voltage means for supplying the plates of said first and second tubes, amplifying means including said first thermionic tube, independently amplifying said modulated alternating input voltage, independent of any alternating voltages across said output conductance, rectifying means including said auxiliary plate and associated cathode converting said independently amplified modulated alternating input voltage to a unidirectional voltage, in direct proportion to the amplitudes of said modulated alternating voltage, a primary negative bias for adjusting the grid of said second tube to substantially cut off the plate current of said tube, and a positive secondary bias connected in a series relation with said primary bias, said secondary bias being derived from said unidirectional voltage, and directly proportional thereto, whereby a constant ratio is maintained between the magnitude of the alternating current through the output conductance and the magnitude of said alternating current output conductance, independent of variations in amplitude of said amplitude-modulated alternating voltage.

7. A circuit for removing amplitude modulation from an amplitude-modulated alternating voltage, said circuit having two alternating current conductances in a series relation, one of said conductances being large in comparison with the other, one of said conductances consisting of the cathode-plate alternating current conductance of a thermionic tube having cathode, plate and grid, continuous voltage means energizing said plate, input-terminal means impressing an amplitude-modulated alternating voltage upon said conductances, rectifying means energized independent of any alternating voltages across said cathode-plate, converting a large multiple of said modulated alternating voltage into a unidirectional voltage directly proportional to the amplitudes of said modulated alternating voltage, and bias means connected to said grid, having a primary negative bias in series relation with a secondary bias, said primary bias determining the magnitude of the cathode-plate conductance when no alternating current flows through said conductance, and said secondary bias being derived from said unidirectional voltage, determining conductance of said thermionic tube in relation to the amplitudes of said modulated alternating voltage, whereby a constant ratio is maintained between the magnitude of said larger conductance and the magnitude of the alternating current through said larger conductance, to produce therefrom an alternating output voltage of constant amplitude, across said larger conductance.

8. The method of annulling amplitude modulation of an amplitude-modulated alternating voltage, said method comprising introducing a proportion of said voltage in series relation with

a first electric-conduction path serially connected with a second electric-conduction path, proportioning said second conduction path to have large conductance in relation to said first conduction path, independently amplifying said modulated alternating voltage, independent of any alternating voltages across said second conduction path, rectifying said amplified modulated alternating voltage in direct proportion to the amplitudes of said modulated alternating voltage, combining said rectified voltage with a fixed unidirectional voltage, and electrostatically introducing said combined unidirectional voltages across a part of one of said electric-conduction paths, to modify the electric conductance of said path in a predetermined relation with the amplitudes of said modulated alternating voltage, whereby a constant ratio is established, between the amplitude of alternating current and the magnitude of conductance of said second path, and alternating output voltage of constant amplitude is established across said second conduction path.

9. The method of annulling amplitude modulation from an amplitude-modulated alternating voltage, which consists of amplifying said modulated alternating voltage, rectifying said amplified modulated alternating voltage in direct proportion to the amplitudes of said modulated alternating voltage, serially combining said rectified voltage with a fixed unidirectional voltage, and electrostatically introducing said combined voltage across part of a thermionic conductance, modifying said conductance in a predetermined relation to the amplitudes of said modulated alternating voltage, introducing a proportion of said amplitude-modulated alternating voltage in a series relation with a second conductance serially connected with said thermionic conductance, and proportioning the ratio of said thermionic conductance to the second conductance to have a large disparity with unity, whereby a constant ratio is established between the amplitude of alternating current and the magnitude of the larger conductance, and alternating output voltage of constant amplitude established across said larger conductance.

10. In a device for transforming variable-amplitude alternating input voltages to constant-amplitude alternating output voltages, alternating-voltage input terminals, alternating-voltage output terminals, thermionic-tube conductance means including cathode, anode and control-grid; independent amplifier means providing amplification of alternating input voltages, independent of the magnitude of any alternating voltages across said output terminals, and across cathode-anode of said conductance, converter means including a rectifier-anode and connections to said amplifier means, converting said amplified voltages to unidirectional voltages in direct proportion thereto, connections between said output terminals and the cathode and anode of said conductance, and biasing means across said cathode and control-grid having a primary voltage-bias means serially connected with a secondary voltage-bias means, said primary bias determining amount of conductance of said cathode-anode when said input terminals are not energized, and said secondary bias being responsive to the unidirectional voltage of said converter means, said bias means being polarized in relation to each other and to the characteristic conductance of said cathode-anode to provide constant amplitude alternating output voltage.

independent of amplitude variations of the alternating input voltage.

11. A circuit for removing amplitude modulation from an amplitude-modulated alternating input voltage, said circuit having two alternating current conductances in a series relation, one of said conductances being proportioned to be large in relation to the other, one of said conductances including the cathode-plate conductance of a thermionic tube having cathode, plate and grid; continuous voltage means energizing said plate, input-terminal means impressing amplitude-modulated high-frequency voltage upon said conductances, output-terminal means supplying constant amplitude voltages of said high-frequency, rectifying means responsive to amplitude-modulated voltage of said input terminals, independent of any alternating voltages across said out-

put terminals, and across said cathode-plate, converting a multiple of the amplitude-modulated input-terminal voltage to a unidirectional voltage, directly proportional thereto, connections 5 between said larger conductance and said output-terminals, and bias means connected across said grid-cathode having a primary voltage-bias in series relation with a secondary voltage-bias, said primary bias determining amount of cathode-plate conductance when no alternating current flows therethrough, and said secondary bias being responsive to said unidirectional voltage, said bias means being polarized in relation to each other and to said cathode-plate conductance, whereby a constant ratio is maintained 10 between the magnitude of said larger conductance and the alternating current therethrough.

EDWARD H. LANGE.
